SHOE SEWING MACHINE

Bernard T. Leveque, Wenham, Mass., assignor to
United Shoe Machinery Corporation, Paterson,
N. J., a corporation of New Jersey

Original application March 12, 1935, Serial No.
10,621. Divided and this application May 12,
1936, Serial No. 79,282

3 Claims. (Cl. 112—38)

The present invention relates to shoe sewing machines and more particularly to curved hook needle lockstitch sewing machines adapted to sew the outsole to the welt and upper of a welted shoe.

The object of the invention is to provide a needle and awl mechanism of improved construction particularly adapted for supporting and actuating the curved awl and curved hook needle of shoe sewing machines of the class referred to.

With this object in view, the present invention consists in the construction, combination, and arrangement of parts hereinafter described and claimed, the advantages of which will be obvious to those skilled in the art from the following description.

The present application is a division of applicant's pending application Serial No. 10,621, filed March 12, 1935, which fully illustrates and describes a lockstitch outsole shoe sewing machine employing a curved awl and a curved hook needle. In the drawings accompanying the present application only so much of this machine is illustrated as is necessary to enable the construction and mode of operation of the needle and awl mechanism to be understood.

Referring to the drawings, Figure 1 is a detail view in side elevation of the head of a shoe sewing machine embodying the invention, showing the needle and awl mechanism and certain of the other stitch-forming devices; Figure 2 is a detail sectional view of the supporting structure for the needle, awl, and needle guide, taken along the line 2—2 of Figure 3; Figure 3 is a detail sectional view taken along the line 3—3 of Figure 2, illustrating the needle segment and needle guide; Figure 4 is a detail sectional view of the awl segment, taken along the line 4—4 of Figure 2; and Figure 5 is a detail sectional view taken along the line 5—5 of Figure 2.

The work feeding mechanism is of that type in which the work is fed intermittently by the cooperating action of a work-support and presser foot constructed and arranged to engage respectively the welt and outsole of a shoe. Referring to Figure 1, the work support is indicated at 2, and the presser foot at 4, both members being mounted on a feed carriage 6, which is mounted on fixed guides 8 and 10 for advancing and retracting movements to feed the work past the stitch-forming devices, of which the curved awl and the curved hook needle are indicated respectively at 12 and 14.

In addition to the needle, the thread handling devices comprise a needle threading looper 16, a

thread arm 18 for drawing out a bight of thread between the looper and the work, a loop taker 20 in the form of a rotary shuttle for passing a loop of needle thread over the locking thread case, a loop spreader 22 to spread the loop for the loop taker, a take-up, a thread lock, and a needle thread pull-off or thread measurer. The construction and operation of these devices is fully explained in co-pending application Serial No. 10,621 to which reference has been made.

The curved awl 12 and the curved hook needle 14 are clamped respectively in the awl segment 24 and the needle segment 26, which segments are mounted to oscillate concentrically upon a fixed stud 28. The needle and awl segments are so supported that the needle and awl are in the same vertical plane and operate in this plane without any movement back and forth in the direction of feed. The needle guide indicated at 30 is secured to a hub 32 and this hub is also supported from the stud 28.

As affording a simple and compact construction and one which permits a relative adjustment of the needle and awl segments to bring the needle and awl into the same plane upon a change in the size of either the needle or the awl, or when for any reason these parts become displaced with relation to each other, the needle and awl segments and the hub of the needle guide are arranged on the stud 28 as follows. The hub of the needle guide and the awl segment are mounted in line with each other directly on the stud and the needle segment is mounted on the hub of the needle guide between a flange on the hub of the needle guide and a plate 34 mounted on the stud 28 between a shoulder on the stud and the adjacent end of the hub of the needle guide, the plate being held from rotation by a pin 36 projecting from the plate into the arm 38 of the fixed bracket in which the stud is secured. Between the hub of the needle guide and the awl segment 24 a plate 40 is interposed and is pressed yieldingly against the adjacent end face of the hub of the needle guide by coiled springs 42 seated in recesses in the awl segment. The awl segment is mounted on the stud 28 between the plate 40 and a fixed bracket arm 44. The springs 42 thus tend to force the hub of the needle guide with the needle segment mounted thereon and the awl segment in opposite directions and hold these parts securely in position with the awl segment bearing against the bracket arm 44 and with the hub of the needle guide and the needle segment bearing against the fixed plate 34. One end of the stud 28 is securely clamped

in the bracket arm 38 by means of a binding bolt 46 and the other end of the stud extends through a supporting perforation in the bracket arm 44. At its end adjacent the bracket arm 44 the stud 28 is provided with an internal screw thread engaged by an adjusting screw 48, the flanged head of which engages the outer surface of the bracket arm 44. This screw provides a means for moving the stud 28 longitudinally when released by the clamping bolt 46 to adjust the awl and needle segments relatively to each other longitudinally of the stud to thereby bring the needle and awl into the same vertical plane.

The needle and awl segments are actuated, as hereinafter described, to cause the needle and awl to enter and withdraw from the work. To actuate the needle guide in the desired manner so as to support the needle properly during its work piercing and loop drawing movements, the plate 40 which bears against the end surface of the hub of the needle guide is connected to the awl segment by means of pins 50 rigid with the plate and projecting into recesses in the hub of the awl segment. The movements of the awl segment thus tend to move the needle guide through the frictional engagement of the plate 40 with the hub of the guide and the guide is actuated in the desired manner.

The needle and awl are actuated from the cam shaft of the machine by separate trains of mechanism, each train comprising a lever in engagement with a cam on the shaft and a link movable into and out of engagement with the lever. These trains of mechanism, similar to those actuating the work feeding and thread handling devices, are illustrated and described in the co-pending application Serial No. 10,621 above referred to. The link for actuating the awl is pivotally connected at its forward end to the downwardly extending arm of a bell crank 52 pivotally mounted in a fixed portion of the machine frame on the supporting shaft 54. The forward end of the horizontal arm of the bell crank 52 is provided with a gear segment 56 meshing with teeth formed on the awl-carrying segment 24. To actuate the needle, the forward end of the

link of the needle-actuating train of mechanism is pivotally connected to the downwardly extending arm of the bell crank 58 pivotally mounted on the shaft 54 beside the bell crank 52. The forward end of the horizontal arm of the bell crank 58 is provided with a gear segment 60 meshing with teeth on the needle-carrying segment 26.

The nature and scope of the invention having been indicated, what is claimed is:

1. A shoe sewing machine having, in combination with the other stitch forming and work feeding devices, a curved hook needle and a curved awl arranged to operate in the same plane and to enter the work from opposite sides, a needle guide, a supporting pivot stud, a needle guide carrier mounted on the stud, a needle carrier journaled on the hub of the needle guide carrier, an awl carrier mounted on the stud, a friction plate driven by the awl carrier, and yieldingly pressed against the needle guide carrier, and means for adjusting the supporting stud with the needle guide and needle carrier with relation to the awl carrier longitudinally of the stud.

2. A shoe sewing machine having, in combination with the other stitch forming and work feeding devices, a curved hook needle and a curved awl arranged to operate in the same plane and to enter the work from opposite sides, a needle guide, carriers for the needle, awl, and needle guide, and a frictional connection between the carriers for the needle guide and awl for actuating the needle guide.

3. A shoe sewing machine having, in combination with the other stitch forming and work feeding devices, a curved hook needle and a curved awl arranged to operate in the same plane and to enter the work from opposite sides, a supporting pivot stud, needle and awl carriers mounted on the stud, yielding means holding said carriers separated longitudinally of the stud, and means for adjusting the stud together with one of said carriers with relation to the other carrier longitudinally of the stud.

BERNARD T. LEVEQUE.
